UNITED STATES PATENT OFFICE.

WALTER E. INGHAM, OF NEWINGTON, CONNECTICUT, ASSIGNOR TO PRATT & WHITNEY COMPANY, OF NEW YORK, N. Y., A CORPORATION OF NEW JERSEY.

LATHE.

Application filed September 2, 1921. Serial No. 498,151.

To all whom it may concern:

Be it known that I, WALTER E. INGHAM, a citizen of the United States, residing at Newington, in the county of Hartford and State of Connecticut, have invented certain new and useful Improvements in Lathes, of which the following is a specification.

This invention relates to lathes and particularly to improvements in the carriage and apron mechanism thereof. The primary object of the invention is accordingly to generally improve the construction of lathe apron mechanisms.

It is an object of the invention to provide an improved interlocking means between the carriage feed shaft and feed screw whereby both such elements cannot be in driving engagement simultaneously.

It is another object of the invention to support the tool operating worms on the feed shaft in an improved manner.

A further object of the invention is to provide a clutch on the carriage traversing rack pinion shaft whereby such pinion may be disengaged from its operating hand wheel when desired.

Another object of the invention is to provide an improved lubricating system in the carriage and apron mechanism whereby the bearings therein are at all times supplied with clean lubricant from a central closed oil supply.

With these and other objects in view, my invention consists in the features of construction and operation set forth in the following specification and illustrated in the accompanying drawings. In such drawings annexed hereto and forming a part of this specification, I have shown one embodiment of my invention as applied to a lathe, but it will be understood that the invention can be otherwise embodied and that the drawings are not to be construed as defining or limiting the scope of the invention, the claims appended to this specification being relied upon for that purpose.

Referring to the figures of the drawings:

Figure 1 is a front elevation of a lathe carriage and apron mechanism comprising the invention.

Fig. 2 is a cross sectional view thereof on the line 2-2 of Fig. 1.

Fig. 3 is a horizontal sectional view on the line 3-3 of Fig. 1.

Fig. 4 is a vertical longitudinal section 55 thereof on the line 4-4 of Fig. 3.

Fig. 5 is an end view thereof on the line 5-5 of Fig. 4.

Fig. 6 is a fragmentary sectional view taken on line 6-6 of Fig. 1 and illustrating 60 a feature of the improved lubricating system.

Fig. 7 is a fragmentary sectional view taken on line 7-7 of Fig. 1.

Fig. 8 is a fragmentary detail view of 65 Fig. 7.

Referring more specifically to the drawings by reference characters, 1 indicates a tool carriage longitudinally slidable on ways 2 of the lathe bed. A cross slide 3 is 70 transversely movable on a guideway 4 on the carriage and is adapted to support a tool thereon, as illustrated. The apron mechanism 5 is secured to the carriage by means of bolts 5^a. The carriage may be moved 75 longitudinally on ways 2 under power either by means of a screw 6 or a feed shaft 7 mounted in the apron and suitably operated in the well known manner. The feed shaft 7 is also adapted to operate the cross 80 slide by means of a screw 8 and mechanism hereinafter described. The carriage may be clamped to the bed by clamping mechanism 9. A rod 10, adapted to be operated by a stop 11 or a handle 12, is provided for controlling the operation of screw 6 and feed shaft 7. The means and manner of operating the several elements just described is more fully disclosed in my copending application Serial No. 513,167, filed November 5, 90 1921.

A pair of worms 13 and 14 are splined to the feed shaft and engage worm wheels 15 and 16 respectively for moving the carriage longitudinally and the tool slide transversely. It should be noted that these worms have integral bearing ends 13^a, 13^b and 14^a, 14^b rotatably supported in bearing supports 17 and 18 in the carriage whereby such worms are rendered stronger and more able 95 to perform their driving function. By thus supporting the worms directly in the bearings 17 and 18, the worms are always held in true driving alignment and the worm ends provide bearing supports for the feed shaft and prevent the usual wear of the bearings due to the rotation of the splined feed shaft therein. An adjustable bush- 100 105

ing 19 is secured in the carriage against one end of each worm to hold the worms securely in their proper bearing supports.

The worm wheel 15 is loosely mounted 5 on a shaft 20, a friction clutch 21 splined to the shaft providing means for operatively connecting the worm to the shaft. A knob 22 on a shaft 23 extending through the shaft 20 and threadedly engaging the clutch at 24 10 provides means for opening and closing the clutch. The shaft 20 may be rotated by hand from a hand wheel 25 keyed thereto. A pinion 26 keyed to shaft 20 meshes with a gear 27 keyed to a sleeve 28 slidable on a 15 shaft 29. A pinion 30 on shaft 29 operatively engages a rack 31 on the lathe bed whereby the carriage may be moved longitudinally. The sleeve 28 and a sleeve 32 keyed to the pinion shaft are provided with 20 clutch teeth on their adjacent ends whereby the pinion 30 may be engaged to and disengaged from this shaft. A rotary knob 33 mounted on shaft 29 and threadedly engaging sleeve 28 provides means for sliding the 25 sleeve for engaging and disengaging the pinion clutch.

The worm wheel 16 is loosely mounted on a shaft 34, a friction clutch 35 splined to the shaft providing means for operatively connecting the worm wheel to the shaft. A 30 knob 36 on a shaft 37 extending through the shaft 34 and threadedly engaging the clutch at 38 provides means for opening and closing the clutch. A gear 39 keyed to shaft 34 meshes with a gear 40 in mesh with a pinion 41 on the cross slide screw 8.

When the clutch 21 is closed, the carriage may be moved longitudinally from the feed shaft 7 and when the clutch 35 is closed the 40 cross slide may be operated from the feed shaft 7.

A split nut comprising two halves 42 and 43 is adapted to engage the screw 6 for moving the carriage longitudinally. These 45 nut elements 42 and 43 are mounted for vertical sliding movement between guiding walls 44 and 45. A pin 46 on each element extends into an eccentric slot in a rotary plate 47 on a shaft 48. A handle 49 secured to the shaft is adapted to rotate the plate to move the elements into and out of engagement with the screw.

I prefer to provide an interlock between the clutch 21 and the split nut for the purpose of preventing the simultaneous driving engagement of these elements. A rod 50 has a pin 51 at one end thereof slidably engaging in an inclined slot 52 in a plate on the nut element 43. An element 53 on 55 the other end of the rod is adapted to engage in an annular groove 54 in the clutch 21. With the clutch 21 closed, as in Fig. 3, it will be noted that the groove 54 is out of alignment with the element 53 and 60 therefore the rod cannot slide to the right.

The split nut is necessarily open at this time and cannot be closed until the clutch is opened. These respective positions of the several elements are illustrated in Fig. 4. The pin 51 is in the upper end of slot 52. 70 Movement of the element 53 upwardly to close the nut must necessarily slide the rod to the right. Such action, however, cannot take place until the clutch 21 is open and the groove 54 opposite the element 53. 75 When the clutch is opened, by sliding the same longitudinally, the groove 54 comes opposite the element 53 whereby the element may enter the groove thus permitting the rod to slide to the right and the nut to be 80 engaged with the screw. It will furthermore be noted that when the nut is engaged with the screw, the element 53 is in engagement with the groove 54 whereby the clutch cannot be moved longitudinally to 85 engage the same.

It will be seen that improved mechanism is provided herein for feeding or traversing the carriage by hand or automatically and for feeding or traversing the tool slide automatically. Improved interlocking mechanism is also provided for preventing the simultaneous driving engagement of the carriage feed screw and feed shaft. When operating the carriage automatically, it is 90 desirable to disengage the carriage hand operating means. This operation can be readily performed by rotating the knob 33 to disengage the rack pinion clutch.

For the purpose of properly lubricating 100 the several apron shaft bearings without the use of tubes, oil cups and other complicating mechanism often used for performing this function, I form the carriage and apron mechanism in the novel manner 105 now to be described. I preferably provide two reservoirs 55 and 56 in the body portion of the carriage and apron mechanism, such reservoirs being relatively spaced and located adjacent the ends of the carriage. As 110 illustrated these reservoirs comprise recesses formed within the adjacent faces of the carriage and apron mechanism at 55^a, 55^b and 56^a, 56^b, these parts being securely bolted together. A duct 57 is formed in 115 the apron and extends longitudinally of the carriage into communication with both reservoirs through ducts 58 and 59. The reservoirs may be filled through a filler hole 60 in the reservoir 55, such hole being 120 adapted to be closed by a threaded plug 61. The reservoir 56 is provided with an overflow hole 62 whereby the operator may know when both reservoirs are full.

The apron 5 is preferably provided with 125 an integral rib 63 over each shaft bearing therein and a duct 64 is formed within such rib whereby communication between the main duct 57 and the bearings is provided. A felt pad 65 is inserted at the top of each 130

duct 64 to prevent the oil from flowing too rapidly to the bearings.

In operation, the reservoirs are filled through the opening 60, the overflow hole 52 indicating when the reservoirs are full. The oil from the two reservoirs passes through the ducts 58 and 59 and into the duct 57 and gradually seeps through the felt pads into ducts 64 to lubricate the several bearings. It will be noted that the entire lubricating system is entirely enclosed within the body portion of the mechanism whereby the bearings are at all times provided with clean lubricant, any objectionable projection of parts is eliminated and the system cannot become broken or out of order so long as clean lubricant is supplied to the reservoirs.

It will be understood that in thread cutting operations, the tool carriage is fed along the bed by means of the lead screw 6. Such a cutting operation ordinarily requires several repeating cuts of the tool along the work and, of course, at the end of each cut, the carriage and tool must be returned to the initial starting position to begin another cut. Ordinarily, at the end of a cut along the work, the nut elements 42 and 43 are disengaged from the lead screw 6 and the carriage returned manually by means of the hand wheel 25 and its mechanism cooperating with the rack 31. After disengaging the nut elements from the screw and moving the carriage back to its initial position, the said elements must be re-engaged with the screw for performing the next cut. Such re-engagement may be made by grasping the handle 49 to close the nut elements onto the lead screw and then adjusting the carriage one way or the other until the nut elements re-engage the screw. I provide the following described improved means, however, whereby the screw may be readily and quickly re-engaged with the carriage in its initial position without requiring any such adjusting or "justifying" operation.

Within a horizontal bore 66 formed in an end wall of the carriage, I mount an elongated element 67, such element being held within the bore by means of a head 68 on one end thereof and a piece 69 pinned to its other end. It will be noted that this element is positioned transversely of and directly beneath the lead screw 6 and that it is provided with teeth 70 formed therein and in meshing engagement with the threads of the screw, the screw threads thereby forming a rack engaged by the element. A knurled knob 71 is frictionally mounted on the head 68, the inner portion of the knob being provided thereon with a pair of indicia or graduations 72 180° apart and adapted to cooperate with an indicium 73 on the carriage. While I have illus-

trated only two indicia marks 72 on the knob, it will be understood that other numbers of marks may be used thereon if desired, it only being essential that the same be equally spaced on the knob and that the number of teeth 70 be a multiple thereof.

In operation, the carriage is first manually moved to the initial starting position and the nut elements 42 and 43 are engaged with the screw. The operator now grasps the knob 71 and rotates the same on the element 67 to a position to register one of its graduations 72 with the mark 73 on the carriage. The feeding and cutting operation is now started, the tool being engaged with the work and the carriage being fed therealong by the rotation of the screw 6. It should be noted that as the carriage is fed along by the rotation of the screw, the element 67 acts merely as a nut on the rotating screw and therefore does not rotate.

At the end of the cutting operation the feed is stopped by stopping the rotation of the screw in the usual manner. The nut elements are now disconnected from the screw and the carriage manually returned by rotating the hand wheel 25. The screw is idle during this traversing movement and acts as a rack to rotate the elements 67 and knob 71 as the carriage moves therealong. Since the number of teeth 70 are a multiple of the graduations on the knob 71, the nut elements 42 and 43 will always be in a screw meshing position whenever one of the graduations 72 registers with the mark 73, it being understood that the knob is originally set with such graduations in registry. The carriage is quickly returned to approximately its initial starting position and when one of the graduations 72 is in registry with the mark 73, the nut elements may be readily re-engaged with the screw.

It should be particularly noted that the frictional mounting of the knob 71 on the element 67 provides means whereby the knob may at any time be adjusted to a desired position of registry. It should furthermore be understood that the element 67 rotates only when the screw is stationary and the carriage is being moved therealong, the element acting thereby to indicate the nut and screw meshing positions of the carriage whenever the carriage is disengaged from the screw.

What I claim is:

1. In a lathe, the combination of a tool carriage, a feed shaft, a feed screw, mechanism comprising a clutch for moving the carriage longitudinally upon rotation of the feed shaft, mechanism comprising a nut for engaging the screw to move the carriage longitudinally, interlocking means between the said two mechanisms comprising a rod,

- and means operatively connecting the rod with one of the said mechanisms whereby the rod is moved in two directions thereby, the operative connection between the two mechanisms and the rod being such that the nut and clutch can not be in the operative engaged position simultaneously. 5
2. In a lathe, the combination of a tool carriage, a feed shaft, a feed screw, mechanism comprising a clutch for moving the carriage longitudinally upon rotation of the feed shaft, mechanism comprising a nut for engaging the screw to move the carriage longitudinally, interlocking means between the said two mechanisms comprising a longitudinally slideable rod, means operatively connecting the rod with the nut mechanism whereby the rod is moved longitudinally in both directions thereby, and means adapted 10 to be moved by the rod into and out of engagement with the clutch, the operative connection between the two mechanisms and the rod being such that the nut and clutch cannot be in the operative engaged position simultaneously. 15
3. In a lathe, the combination of a tool carriage, a feed shaft, a feed screw, mechanism comprising a clutch for moving the carriage longitudinally upon rotation of the feed shaft, mechanism comprising a nut for engaging the screw to move the carriage longitudinally, and interlocking means between the said two mechanisms comprising a longitudinally slideable rod extending 20 transversely of the clutch axis, and an inclined slot and pin connection between the nut mechanism and rod whereby the rod is moved longitudinally in both directions by the movement of the nut mechanism, the operative connection between the two mechanisms and the rod being such that the nut and clutch cannot be in the operative engaged position simultaneously. 25
4. In a lathe, the combination of a tool carriage, a feed shaft, a feed screw, mechanism comprising a clutch for moving the carriage longitudinally upon rotation of the feed shaft, mechanism comprising a nut for engaging the screw to move the carriage longitudinally, interlocking means between the said two mechanisms comprising a longitudinally slideable rod extending transversely of the clutch axis, the clutch having 30 an annular groove extending therearound, and means on the rod adapted to be moved into and out of the groove, the operative connection between the two mechanisms and the rod being such that the nut cannot be 35
- operatively engaged to move the carriage while the clutch is engaged and the operative engagement of the nut to move the carriage being adapted to move the rod longitudinally and thereby the last named means 40 into the said groove to prevent the operative engagement of the clutch. 45
5. In a lathe, the combination of a bed, a tool carriage slidably mounted thereon, a feed shaft, a toothed rack on the bed, a shaft 50 on and extending transversely of the carriage, a pinion mounted on the shaft and engaging the rack, an operative connection between the feed shaft and pinion shaft, and a clutch on the pinion shaft whereby the 55 pinion may be disengaged from its shaft when desired. 60
6. In a lathe, the combination of a tool carriage and apron mechanism, a pair of spaced reservoirs formed in the body portion of the carriage, a duct formed in the body portion of the carriage and apron mechanism in communication with both reservoirs, one reservoir being provided with a filler hole and the other reservoir with an 65 overflow hole, and a plurality of ducts formed in the body portion of the apron in communication with the first named duct and extending to the shaft bearings in the apron. 70
7. In a lathe, the combination of a tool carriage and apron mechanism, a pair of spaced reservoirs formed in the body portion of the carriage adjacent each end thereof, a horizontal duct formed in the body portion of the apron and extending longitudinally of the carriage in communication with both reservoirs, one reservoir being provided with a filler hole and the other reservoir with an overflow hole, and a 75 plurality of ducts formed in the body portion of the apron in communication with the first named duct and extending to the shaft bearings in the apron. 80
8. In a lathe, the combination of a tool carriage and apron mechanism, an oil reservoir formed in the body portion thereof, a plurality of bearings in the apron, the apron being formed with substantially vertically extending integral ribs thereon over 90 the bearings, and ducts formed in the body portion of the apron within the said ribs to provide communication from the reservoir to the bearings in the apron. 95
- In testimony whereof, I hereto affix my 100 signature.

WALTER E. INGHAM.
